UNITED STATES PATENT OFFICE.

WILLIAM C. BAYLESS, OF JEFFERSON CITY, AND JACKSON S. DALLAS, OF KNOXVILLE, TENNESSEE.

FENCE.

SPECIFICATION forming part of Letters Patent No. 741,095, dated October 13, 1903.

Application filed April 10, 1903. Serial No. 152,035. (No model.)

To all whom it may concern:

Be it known that we, WILLIAM C. BAYLESS, residing at Jefferson City, in the county of Jefferson, and JACKSON S. DALLAS, residing at Knoxville, Knox county, State of Tennessee, citizens of the United States, have invented new and useful Improvements in Fences, of which the following is a specification.

Our invention relates to certain new and useful improvements in fences of the type in which the rails, upright cleats, lateral braces, and other component parts are secured together by means of wire, and the novelty resides in the particular manner of wiring the said parts of the fence together.

It is the object of our invention to provide a fence which may be economically constructed and which shall be strong and durable and adapted to resist the attack of stock and the force of the wind.

In order that the invention may be fully understood, we have illustrated the same in the accompanying drawings, in which—

Figure 1 is perspective view illustrating a portion of a fence constructed according to our invention. Fig. 2 is a partial plan view illustrating the manner of wiring employed at the top of the fence. Fig. 3 is a detail view illustrating one form of loop and stay-wires employed at the center of the upright cleats. Fig. 4 is a transverse sectional view illustrating additional means of binding the rails together. Fig. 5 is a detail view illustrating a modification of the loop and stay-wires shown in Fig. 3. Fig. 6 is a detail view illustrating the manner of wrapping the wire about a stake and adjacent brace, and Fig. 7 is a partial plan view illustrating a modification of the manner of wrapping the top wire about the cleats and braces shown in Fig. 2.

Referring now to the drawings, 1 indicates the rails; 2, the upright cleats; 3, the transverse braces, and 4 the riders supported in the crotches of said braces, these parts being of wood and of the usual or any preferred construction—that is to say, they may be of split, sawed, or dressed timber or be made from the wood in its natural state.

In constructing the fence two rails are laid one upon the other at their end portions, and a piece of wire 5 is passed loosely around the

same and twisted at its ends. A cleat 2 is inserted about seven inches at its lower end through the wire loop 5 from opposite directions on the respective sides of the fence and then raised upward and toward each other to bring them to an upright position, as shown, this operation partly twisting the loop 5 and binding the two ends of the lowermost rails 1 of adjacent panels securely together and binding also the lower ends of the cleats 2 firmly against said rails. The end of one rail only may be used in this lower loop and the end of the ground-rail of the adjacent panel forced down upon this after the cleats are raised to a perpendicular position. Other rails are now placed at their ends one upon the other in the usual manner until, say, three rails have been so arranged, when a loop of wire 6 is now passed around the two cleats 2, the rails being pressed down so as to get the loop 6 as far down on the cleats as possible. The cleats are then drawn firmly against the rails by means of the loop 6 and the ends of said loop are then twisted. 75 We then fill in two more rails, and then cross the braces 3 over the topmost rail and bind said braces together at their point of intersection by means of the wire loop 7. The lower ends of these braces are spread apart, 80 so that the crotch formed will rest firmly on the upper rail and their lower ends on the ground. We then place the riders 4 in the upper crotch of the braces with their ends overlapping, as usual. The braces 3 are designed to be secured at each side of the fence to the wire loop 6, and this may be done in one of two ways. The wire loop 6 may be formed by wrapping the wire twice around the cleats 2, and the stay-wire 8 may then be 85 secured to the upper strand-wire of the loop at one side of the fence and passed around the braces 3, and a similar stay-wire is secured to the lower strand-wire of the loop and secured to the opposite brace 3, this construction insuring that as the fence settles or the braces spread apart the tension on the two strands of the loop 6 exerted by the stay-wires 8 will operate to draw the loop about the cleats 2 more firmly. The second mode of forming 90 this connection is illustrated in Fig. 5, in which the wire 9 is passed one and a half times

around the cleats 2 between two of the rails and its free ends secured directly to the respective braces on opposite sides of the fence. Thus as the fence settles or the braces 3 spread 5 apart the tension will be directly upon the wire 9, which will operate to draw said wire more firmly about the cleats 2. The fence is now provided with a top securing-wire 10. This upper securing-wire requires to be very 10 strong and is wrapped about the cleats and braces in such manner as to provide two strands of wire to resist pressure adapted to be exerted thereon, as explained later on. To this end the wire 10 is passed over one 15 cleat and crossed and placed around the other cleat, and the two strand-wires are then brought together and passed under the upper end of one of the braces 3, that adjacent to the cleats, and are then separated and looped 20 over the upper end of the other brace. A stay-bar 11 is now inserted at its upper end between the wires in the crotch formed by the cleat 2 and the adjacent brace 3 in such manner that two strands of the wire 10 will be on 25 the upper side of said stay-bar and two strands on the lower side, and the opposite end of said stay-bar is then pressed downward and at its lower end secured by a wire 12 to one of the other of the rails 1. In this operation the tendency 30 will be to raise the cleats 2 and press downward the braces 3, thus pressing the parts of the fence more firmly together, while at the same time, owing to the manner of wrapping the wire 10 about the cleats and braces, said 35 cleats will be firmly pressed against the riders 4, said riders will be firmly pressed down in the crotch of the braces 3, and the braces 3 will have their upper ends brought firmly against the riders 4. It is to be observed 40 also that in this movement of the stay-bar 11 there will be no tendency to vary the relative positions of the cleats and braces 3, the tension being exerted in substantially straight transverse lines. As a further means of binding 45 the parts of the fence firmly together we may secure to each side of the bottom loop 5 a wire 13, the upper portion of which is wrapped around the upper end of the stay-bar 11 before the same is turned downward 50 in the manner previously described to bind the wire 10 about the cleats and braces, whereby in this operation the wire 13 will be drawn upward, exerting pressure on the wire loop 5, tending to raise the rails against the resistance 55 of the braces 3, thus binding the overlapping ends of the rails more firmly together. In addition the wire 13 tends to hold the loop 5 from slipping downward on the cleats 2, as this loop 5, it will be understood, forms the 60 sole support for the lower rails of the fence.

We have described the construction at one end of a panel; but it will be understood that the opposite end of the panel is constructed in the same way and that the riders and rails 65 of one panel overlap with the riders and rails of the adjacent panel at each end in the usual manner. In order to further stay the fence

to prevent its being blown over or knocked over by stock, we may drive into the ground a stake 14 adjacent to each brace 3 in a direction substantially at right angles to the brace, as shown, and then secure the brace to this stake by means of a wire 15, which is passed around the stake and brace in the side crotches formed thereby and is then given one twist and the free ends passed around the stake and brace in the upper and lower crotch, respectively, the ends of the wire being then twisted together. By this manner of securing the brace to the stake all liability of movement of the brace relative to the stake is prevented and the brace cannot be moved by any pressure or force less than that which would be required to tear the stake bodily from the ground.

In Fig. 7 we have also shown a modification in the manner of arranging the upper securing-wire 10. This differs from the preceding construction simply in the fact that the wire is not crossed between the two cleats 2; but otherwise the arrangement is the same.

Having thus fully described our invention, what we claim as new, and desire to secure by Letters Patent of the United States, is—

1. In a fence, in combination with the rails 95 1, cleats 2, braces 3 and riders 4, of a securing-wire looped over the upper end of one of said braces and around the upper ends of said cleats and having the intermediate double-strand portion passed under the upper 100 end of the other brace, of a stay-bar inserted between the two double strands of said securing-wire between one of the cleats and the adjacent brace, and having its lower end turned downward and wired to one of the 105 rails of the fence, for the purpose described.

2. In a fence, in combination with the rails 1, cleats 2, braces 3 and riders 4, of a securing-wire looped about the upper end of one of said braces and around the upper ends of said cleats, and crossed between said cleats, and having its intermediate double-strand portion passed under the upper end of the other brace, of a stay-bar having its upper end inserted between the double strands of 110 said securing-wire in the space between one of said cleats and the adjacent brace and its lower end turned downward and wired to one of the 115 rails of the fence, for the purpose described.

3. In a fence, in combination with the rails 1, cleats 2, braces 3 and riders 4, a securing-wire passed around the upper ends of said cleats and said braces, a lever having its upper end inserted between the strands of said wire, and a wire connected to the lowermost rails of the fence and to the outer end of said lever, said lever being turned downward at its inner end and wired to one of the rails of the fence whereby to produce a tension on the 125 rail at its outer end and to draw the securing-wire firmly about the ends of said cleats and braces.

4. In a fence, the combination with the cleats

2 and the rails having overlapping ends extending between said cleats, of the braces 3, a wire passed twice around said cleats between two of the rails and having its ends secured together, and stay-wires secured at one end to one strand of said wire on one side of the fence and on the other side to the other strand of said wire, the opposite ends of said stay-wires being secured to said braces.

In testimony whereof we have hereunto set our hands in presence of two subscribing witnesses.

WILLIAM C. BAYLESS.
JACKSON S. DALLAS.
